UNITED STATES PATENT OFFICE.

SAMUEL W. HORST, OF LEMOYNE, PENNSYLVANIA, ASSIGNOR OF ONE-HALF TO
WALTER MERTZ, OF LEBANON, PENNSYLVANIA.

WINDOW CONSTRUCTION.

1,170,816.

Specification of Letters Patent.

Patented Feb. 8, 1916.

Application filed January 23, 1914. Serial No. 813,940.

To all whom it may concern:

Be it known that I, SAMUEL W. HORST, a citizen of the United States, residing at Lemoyne, in the county of Cumberland and 5 State of Pennsylvania, have invented a new and useful Window Construction, of which the following is a specification.

The present invention appertains to a novel and improved window construction, 10 and relates more particularly to a unique means for mounting a sash within a window casing or frame.

It is the object of the present invention to provide means for mounting a sash within a 15 window casing or frame, which shall eliminate with the ordinary wooden stops and parting strips, and which shall serve to effectively close the gaps between the sash and window casing, so as to exclude the elements. 20 Another object of the present invention is to provide means of the nature indicated which shall permit the window sash to be readily removed and replaced, without the necessity of detaching any of the parts which 25 normally retain the sash in position.

A further object of the present invention is to provide unique means for mounting the sash within a window casing, which will permit of the expansion and contraction of the 30 sash, as well as the window casing, without interfering with the sliding movements of the sash.

Another object of the present invention is to provide sheet metal sashways attachable 35 to the jambs of a window casing in a peculiar manner, and with which the stiles of the sash are engageable in a unique manner, to carry out the functions desired.

With the foregoing and other objects in 40 view, which will be apparent as the description proceeds, the invention resides in the combination and arrangement of parts and in the details of construction hereinafter described and claimed, it being understood that 45 changes in the precise embodiment of the invention herein disclosed, can be made within the scope of what is claimed, without departing from the spirit of the invention.

The invention has been illustrated in its 50 preferred embodiment in the accompanying drawing, wherein:—

Figure 1 is a fragmental elevation of the improved window construction, taken from the inside. Figs. 2 and 3 are sectional views

taken on the lines 2—2 and 3—3 of Fig. 1, 55 respectively.

In the drawing, only a single jamb of the window casing, and a single stile of the sash, are illustrated, although it is to be understood that the present improvements are incorporated or duplicated at both sides.

The jamb of the window casing has been designated by the numeral 1 and the outer and inner sills by the numerals 2 and 2' respectively. The respective or complementary stile of the sash has been designated by the numeral 3, and the lower rail by the numeral 4. The lower rail is seatable upon the outer sill adjacent the inner one.

It is of course understood, that the present 70 invention may be applied to both sashes of a window construction, although only a single sash is illustrated and described herein.

In carrying out the present invention, the face of the jamb 1 is left smooth, with the 75 exception of the narrow slots or cuts herein-after described, the usual stops and parting strip being eliminated. In lieu of the usual stops and parting strip for mounting the sash within the casing, there is employed a 80 sheet metal channel or guide member 5 forming a sash guide or sashway to receive the respective edge of the sash, or the stile 3 thereof. The channel member 5 is of a width slightly less than the thickness of the sash, 85 and its flanges are relatively wide, the flanges being bent back or reflexed so that their edges project beyond the back of the channel, as at 6. The channel member 5 is disposed vertically, and the edges 6 of its dou- 90 bled flanges are inserted snugly into spaced upright slots or kerfs 7 cut in the face of the jamb 1, in order that the back of the channel member rests against the face of the jamb, as clearly seen in Fig. 3 and to hold 95 the channel or guide member against lateral movement. The remote faces of the reflexed portions 6, are preferably flush with the faces or sides of the sash, as will hereinafter more fully appear. The channel member 5 100 extends from the sill to the upper end or meeting rail of the sash, the sash being slightly raised in Fig. 1, it not being necessary to continue the channel member above the sash, as is necessary where a parting 105 strip is employed.

A sheet metal strip 8 is secured upon the outer sill 2 underneath the sash, by means of

the brads, tacks, or other securing members 9 engaged through the edge portions of the strip 8 and taking into the sill. The strip 8 is provided with an upstanding doubled 5 portion 10 forming a bead or rib disposed underneath the inner face of the sash and adjacent the inner sill 2'. The lower inner corner of the channel member 5 is cut away, as at 11, to accommodate or cope with, the 10 respective end of the outstanding crimp or bead 10.

Strips 12 are secured to the inner faces of the stile 3 and rail 4 adjoining the outer edges of the said stile and rail, and the stile 15 3 is provided with the side rabbets 14 receiving the beads or crimps 15 of the flanges of the channel member 5 formed by the reflexed portions 6. The outer edge portions of the strip 12 secured to the stile 3, overlap 20 the inner bead 15, as seen in Fig. 3. The strips 12 are attached to the sash adjacent the rabbets by brads, tacks, or other securing members 13 engaged through the strips adjoining their inner edges and taking into the 25 sash, thereby leaving the outer edges of the strips free.

The lower rail 4 of the sash is also provided with an inner lower rabbet 14 for receiving the bead or rib 10 when the sash is 30 lowered, the lower or free edge of the strip 12 secured to the rail 4, depending over the rabbet 14 of the rail 4 and being adapted to slide over the inner side of the bead 10, so that the bead will be snugly received between 35 the rabbet 14 and the strip 12 of the lower rail and so that the said strip 12 will slip between the bead 10 and the inner sill 2', when the sash is lowered against the sill.

From the foregoing, taken in connection 40 with the drawing, it will be manifest that the channel members 5 will permit the sash to slide vertically in an efficient manner, the channel members being retained in engagement with the jambs of the window casing, 45 by the sash, and it being noted, that when the sash is raised sufficiently, the same may be lifted out of engagement with the channel members 5, to remove the sash for any purpose whatsoever. Conversely, the sash 50 may be readily inserted into the channel members or sashways 5. When the sash is removed, the channel members 5 may be withdrawn from the jambs of the window casing, in order that the faces of the jambs 55 will be unencumbered for the purpose of painting, varnishing or otherwise treating them. The channel members 5 may be readily engaged with the jambs by simply inserting the wings or reflexed edge portions 6 into the grooves or slots 7, after which, the 60 sash may be engaged between the respective

channel members. It is of course understood that where a pair of sashes are employed, each sash will be provided with the channel members, the respective channel 65 members being independent of each other, and no parting strip being necessary.

The channel member 5 is sufficiently resili- 70 ent to yieldingly receive the stile 3, whereby the sash will be permitted to expand and contract, without interfering with the efficiency of the device, the yielding or resili- 75 ent channel member also assisting in excluding the elements. These features are especially manifest, in connection with the strip 12 secured to the stile and coacting with the inner bead 15 of the channel member, the free or outer edge of the strip 12 yieldingly engaging the said bead to assist in excluding the elements, and in finishing 80 the window structure.

The lower weather strip 8 secured to the sill is also of advantage, for excluding the elements when the sash is lowered, as will be clearly apparent from the foregoing. 85 Particular attention is directed to the fact that the peculiar channel member as formed is in the shape of an I-member with the flanges at one side engaging the jamb of the window casing, and with the flanges at the 90 other side receiving the sash.

Having thus described the invention, what is claimed as new is:—

In a device of the class described, a stile and a sill; an I-shaped member comprising 95 sash guiding flanges, and holding flanges inserted into the stile; a sash slidable between the guiding flanges and provided in its lower edge with an open sided recess; a strip on the sill and embodying an upstanding flange, the strip being adjustable transversely of the sill to permit the flange there- 100 of to enter the recess and to abut against the sash when the latter is closed, one of the holding flanges being cut away to receive 105 one end of the upstanding flange and to permit an adjustment of said flange toward and away from the sash when the latter is closed; means for securing the strip to the sill; a detachable angle plate; and means for securing 110 the angle plate to the sash, the angle plate constituting a closure for the recess and a guide coöperating with the notched flange.

In testimony that I claim the foregoing as 115 my own, I have hereto affixed my signature in the presence of two witnesses.

SAMUEL W. HORST.
